UNITED STATES PATENT OFFICE.

RAYMOND V. DAVIS, OF DENVER, COLORADO.

SAFETY-CATCH FOR PINS.

1,276,183.

Specification of Letters Patent. Patented Aug. 20, 1918.

Application filed January 11, 1918. Serial No. 211,393.

To all whom it may concern:

Be it known that I, RAYMOND V. DAVIS, a citizen of the United States, residing at Denver, in the county of Denver and State 5 of Colorado, have invented certain new and useful Improvements in Safety-Catches for Pins, of which the following is a specification.

This invention relates more particularly 10 to an improved safety catch especially adapted to jewelry and it has for its primary aim to provide a catch with a rotatable keeper part which will be efficient in operation and simple of construction.

15 The invention further resides in the salient features of construction, and the arrangements and combinations of parts hereinafter described in detail and claimed in a succinct manner, reference being had to the 20 accompanying drawing wherein—

Figure 1 is a side elevation of the improved safety catch embodied in a bar pin;

Fig. 2 is a transverse section through the pin and depicting the catch in elevation;

25 Fig. 3 is a fragmentary longitudinal section through the catch end of the pin; and

Fig. 4 is a view similar to Fig. 2 showing the keeper rotated to have its pin seat register with pin-retaining pocket.

30 Referring to corresponding parts throughout the several views by like characters of reference, the numeral 1 designates the body of the bar pin, 2 the pin part pivoted at one end 3 of the bar, and 4 the safety catch constituting the subject matter of the present 35 invention.

This catch comprises a base or pocket portion having side flanges 5 extending outwardly from the upper part thereof to provide a concave, semi-cylindrical casing into 40 which opens the pin-retaining pocket 6 that is formed in the base. The outer end of this concave casing or guard is closed by a transverse end wall 7 in which is secured one end 45 of a shaft 8 that rotatably supports a cylindrical keeper 9. This keeper is mounted concentrically to its guard or casing 5 and has radially formed therein a pin-receiving groove or seat 10 which opens through its periphery and is adapted to be alined with the retaining pocket or recess 6 upon rotation of the keeper, the peripheral surface of the latter being corrugated or roughened to facilitate the turning thereof.

50 In practice, the pointed end of the pin is

engaged in the outwardly facing seat of the keeper, the latter being disposed substantially as depicted in Fig. 2, and said keeper is then rotated to aline its seat with the pocket 6 of the base when the pin is pressed from the seat into the pocket and held therein until the keeper has been further rotated to disaline the seat and pocket. The pin, owing to its resiliency, may then spring up 60 against the keeper cylinder but will not leave its pocket until the keeper is again rotated to bring the seat 10 into alinement with the pocket, when the pin will automatically spring into the seat so that further rotation of the keeper will bring the 65 pin out for free movement about its pivot 3.

To prevent the rotary keeper from turning too freely, or in an unauthorized manner, the end of the cylinder opposed to the end wall 7 is bored to form a chamber 11 70 in which is disposed a coiled, tensioned spring 12 bearing at one end on the end wall 7 and at its opposite end against the keeper so as to frictionally retain the latter in a set position. By varying the tension on the 75 spring, or by the substitution of different spring, the frictional lock may be increased or decreased accordingly.

The device is simple and efficient in operation, being a sure lock and having no projecting parts to engage in the wearing apparel. The catch is economical in construction since the base may be stamped from sheet metal and requires only a pin or shaft 80 connection for mounting the keeper thereon. 90

What is claimed is:—

1. A safety catch for pins comprising a base having a concave guard and a pin-retaining pocket opening thereinto, said concave guard provided with a transverse end wall, a shaft secured in the end wall, a cylindrical keeper journaled on the shaft concentrically to the guard and formed with a pin-receiving groove registrable with the pocket of the base, the end of the keeper opposed 95 to the end wall being chambered, and a friction-affording coiled spring arranged in the chamber of the keeper to serve as a friction lock therefor.

2. A safety catch for pins comprising a 105 base having a semi-cylindrical guard having a central pin-retaining pocket opening therein, a rotatable keeper journaled concentric to the guard and formed with a peripheral pin-receiving seat registrable with the 110

socket of the base and designed to receive a pin for carrying it past the guard to and from the pocket.

3. A safety catch for pins comprising a guard having a pin retaining pocket and an upstanding wall at one end, and a keeper rotatably carried by the wall in overlying relation to the guard and its pocket, and formed with a peripheral seat for receiving 10 the pin to transfer it to the guard pocket, said keeper serving to keep the pin in said guard pocket.

4. A safety catch for pins comprising a guard formed with a pin-retaining pocket, 15 and a combined keeper and transfer member formed with a pin-receiving cut-out for receiving the pin to deliver it to and taking it from the pin retaining pocket of the guard when communicating therewith, said member being movable to and from a position communicating with the pocket whereby to serve as a keeper for the pin when in said guard pocket.

Copies of this patent may be obtained for five cents each, by addressing the "Commissioner of Patents, Washington, D. C."

5. In a safety catch for pins, a rotary keeper having an axial pin-transfer groove, 25 and a concentric casing formed with a pocket normally closed by the keeper and adapted to register with the groove on rotation of the keeper to receive the pin from the keeper groove for retention therein by 30 the keeper subsequent to a movement of the latter for disalining the groove and pocket.

6. A safety catch for pins comprising a guard having a pin-retaining pocket in its upper face and an upstanding end wall, a 35 cylindrical keeper journaled horizontally in the end wall and overlying the guard and its pocket, said keeper formed with a groove to receive a pin and registrable with the underlying guard pocket for delivering and 40 taking the pin to and from the pocket, and means for holding the keeper against rotation.

In testimony whereof I affix my signature.

RAYMOND V. DAVIS.
